AUTOMOBILE SAFETY GUARD

Filed May 4, 1931

INVENTOR.
Mary E. J. Brown,
BY
Louis Necho
ATTORNEY

UNITED STATES PATENT OFFICE

MARY E. J. BROWN, OF PHILADELPHIA, PENNSYLVANIA

AUTOMOBILE SAFETY GUARD

Application filed May 4, 1931. Serial No. 534,887.

My invention relates to a shield or guard and relates particularly to a shield or guard to be placed in front of the wheels of a vehicle.

5 My invention still further relates to the prevention of any object, such as a person or an animal, from being run over by the wheels of the car and to brush such object from the path of the wheels.

10 My invention has particular adaptability on vehicles, used on farms where animals such as chickens are close by, to prevent crushing or running them over.

15 My invention further relates to a shield or guard to brush aside any snow or slush which may hinder the progress of the vehicle.

20 My invention further relates to a shield or guard to brush aside any glass, tacks or sharp substances which may cause damage to the pneumatic tires.

Another object of my invention is to provide an adjustable device which may be placed out of the way and rendered inoperative by adjusting means.

25 With these ends in view my invention consists of a metal semi-cylindrical guard or shield suspended from the axletree or any other portion of the vehicle.

30 Other objects of my invention, are to provide an improved device of the character described which is easily and economically produced, sturdy in construction, and which has a maximum efficiency and accuracy.

35 With these and other objects in view my invention consists in the following details of construction and combinations of parts, as will be more fully understood from the following specification in which:

40 Figure 1 is a perspective view of my invention applied to a motor vehicle;

Figure 2 is a side elevational view of my invention in an operative and inoperative position;

45 Figure 3 is a plan view of my invention;

Figure 4 is a modified form of my invention showing bristles on the end of my device closest to the ground.

50 Referring to the drawings in which like reference characters indicate like parts in all of the figures, I show an automobile generally

designated as A having front fenders 10 and 11, front wheels 12 and 13 and an axletree 14, having bearing studs 16 and 18 pivoted upon the ends of the axletree.

For purposes of illustration only one 55 guard need be described although two or more guards B are utilized since the guards for the right and for the left wheel are identical in construction.

The guard or shield B, formed of a metal 60 body 20 or any other solid hard material, is semi-circular in cross-sectional area and has extending from near the center of its longitudinal side, an extension 22 having at its end a flange 23 that fits around the axletree 14 65 and a bolt 24 passing therethru to hold the flange 23 rigidly to the axletree. The other side of the guard or shield has an extension 25 and a second flange 26 which is fastened to the bearing stud 18 of the axletree 70 14 and is retained in position by a hub-cap 28.

A slot 30 at the end of the flange permits the bearing stud 18 to slide therein so that the shield remains in position when the front wheels of the vehicle are turned.

At each end of the body 20 of the shield are openings 32 and 34 for a purpose hereinafter to be described. A strap 36 attached to the fender passes thru the opening 32 and holds the guard in operative position. However, to place the guard out of the way or render it inoperative the bolt 24 is loosened, the guard is swung to the position indicated by the dotted lines of Figure 2, the strap inserted in the lower opening 34, and the bolt 85 tightened, whereby the guard is placed out of the way.

In Figure 4 I show a modified shield or guard C similar in construction to the guard B but having at the lower end 38 thereof stiff bristles 40 suitably connected thereto, for the purpose of brushing aside any glass, tacks or other sharp substance which may accumulate in the path of the vehicle and puncture 95 the tires.

Although the invention has been described in considerable detail such description is considered illustrative rather than limiting, as the invention may be variously embodied, 100

and the scope of the invention is to be determined as claimed.

Having thus described my invention, what I claim as new and desire to secure by Letters Patent is:

1. In a shield or guard, a body of semi-circular cylindrical formation, a flange extending from one side thereof to be attached to an axletree of a vehicle, a second flange extending from the opposite side of said body to be attached to one end of the bearing stud of said axletree, there being openings at each end of said body, and means to engage one of said openings to secure said body to a fender of said vehicle.
2. In a shield or guard, a body of semi-circular cylindrical formation, a flange extending from one side thereof to be attached to an axletree of a vehicle, a second flange extending from the opposite side of said body to be attached to one end of the bearing stud of said axletree, there being openings at each end of said body, means to engage one of said openings to secure said body to a fender of said vehicle, and brush elements depending from the lower ends of said body.

In testimony whereof I affix my signature.

MARY E. J. BROWN.
